(57) **CLAIM**

(21) Appl. No.: **29/612,939**

I claim the ornamental design for a combined lipstick casing and lipstick bullet, as shown and described.

(22) Filed: **Aug. 4, 2017**

DESCRIPTION

(51) **LOC (12) Cl.** **28-03**

FIG. 1 is a front view of the combined lipstick casing and lipstick bullet showing the new design;

(52) **U.S. Cl.**

FIG. 2 is a back view thereof;

USPC **D28/90**; D28/87

FIG. 3 is a top view thereof;

(58) **Field of Classification Search**

FIG. 4 is a bottom view thereof;

USPC D28/76, 85-90; D9/624, 606, 726, 725,

FIG. 5 is a right side view thereof;

D9/503-505, 529, 541, 549, 551, 553,

FIG. 6 is a left side view thereof;

D9/559, 560, 561, 564, 574, 575

FIG. 7 is a perspective front view thereof;

CPC A45D 40/00; A45D 40/023; A45D 40/04;

FIG. 8 is a left perspective view with the cover removed and the bullet exposed;

A45D 40/06-065; A45D 40/08

FIG. 9 is a top perspective view with the cover replaced;

See application file for complete search history.

FIG. 10 is a top perspective view with the cover removed and the bullet exposed; and,

(56) **References Cited**

FIG. 11 is a right perspective view with the cover adjacent the casing and the bullet exposed.
